SCREEN AND STORM WINDOW

Charles Rick, Highland Park, Mich.

Application February 19, 1943, Serial No. 476,477

2 Claims. (Cl. 160—182)

My invention relates to a new and useful improvement in a screen and storm window and has for its object the provision of a structure which may be easily and quickly mounted in a window casing without any alterations or mar-ring of appearance of the window casing.

It is another object of the present invention to provide a screen and storm window so constructed and arranged that the windows or screens may be removed from the interior of 10

Another object of the invention is the provision in a storm and screen window of a construction whereby a pair of sashes may be slidably mounted in the supporting frame, one above the other, and so constructed that when the lower is removed, the upper will be retained in position and prevented from moving downward-ly into the position of the lower.

Another object of the invention is the provision of a storm and screen window so constructed and arranged that the shedding of rain, sleet, snow, and the like is most effective and a sifting or seepage of the same into the interior would be avoided.

Another object of the invention is the provision of a storm and screen window construction of the class described so arranged that it will be light, compact, easily handled, and eco-nomically manufactured.

Other objects of the invention will appear hereinafter.

It is recognized that various modifications and changes may be made in the detail of structure illustrated, and it is intended that such varia-tions and modifications shall be embraced within the scope of the claims which form a part hereof.

Forming a part of this specification is a draw-ing in which:

Fig. 1 is a front elevational view of the invention.

Fig. 2 is a fragmentary side elevational view of the supporting frame used in the invention.

Fig. 3 is a sectional view slightly enlarged taken on line 3—3 of Fig. 1 with parts broken away.

Fig. 4 is a prospective view of the invention.

Fig. 5 is a sectional view taken on line 5—5 of Fig. 1.

Fig. 6 is an enlarged sectional view taken on line 6—6 of Fig. 1.

As shown in the drawing, I provide a sup-
porting frame having oppositely disposed side
rails 12 and 13 and oppositely disposed end rails
14 and 15. In use, this frame is mounted in 56

a window casing and forms a permanent part of the building, so that it is not necessary to remove it and replace it at the various seasons. The thickness of the frame is such that it will seat in a window casing and bear against the blind stop so that it does not project outwardly beyond the outer edge of the casing an undesirable distance to mar or deface the appearance of the same.

Formed in the rail 16 is an opening 16 which may be closed by the swingable closure 17. This opening 16 is to permit water to escape from be-tween the conventional window and the window or screen which is mounted in the supporting 15 frame.

This supporting frame may be used as a mount-ing for either storm windows or screens, and in Fig. 1 I have illustrated a window frame em-bodying the upper rail 18, the lower rail 19, and

20 the side rails 20 and 21. As clearly shown in Fig. 3, each of these rails comprises a pair of sections which are secured together and serve as a retainer for the pane of glass 21'. Each of the side rails of the window frame has a tongue 22 which overhangs the edge of the side rail 13 or 12, as the case may be. Each of these side rails 12 and 13 also has a tongue 22' which overhangs the side rails of the window frame which is slidably mounted in the supporting 25 frame so that a sealing connection is thus pre-sented for preventing drafts through the meet-ing faces of the window frame and the support-ing frame. The upper rail 18 is provided with

30 the upwardly projecting tongue 23 which is adapted to overlie the upper rail 14, and this upper rail 14 has the depending tongue 24 which overlies the upper rail 18. The lower rail of the window frame has a depending tongue 25 overlapping the upwardly projecting tongue 26

35 on the upper rail 18' of the lower frame. The lower rail 19' of the lower frame has a tongue 27 which overlies the upwardly projecting tongue 28 on the lower rail 15.

Secured to the under surface 29 of the support-ing frame rail 14 is a jaw spring 30.

The construction is such that when the window frames are positioned in the supporting frame, they may be spread upwardly so as to flex the bow-shaped leaf spring 30 until the tongue 27 40 clears the tongue 28, whereupon the lower edge of the lower window frame may be swung inward-ly to move downwardly into the position shown in Fig. 3, the spring 30 serving to maintain a close contact. The tongue 23 will, when the window frames are in this position, overlie the lower edge

of the frame 14, as shown in Fig. 3. It will be noted that the tongues 24, 25, and 27 serve as effective water sheds to deflect water so that seepage of the same inwardly of the supporting frame is prevented.

This construction permits the removal and replacement of the window frames in the supporting frame from the interior of the building. As shown in Fig. 3, the upper and lower window frames are each provided with an eyelet 31 and 32 connected together by the hook 33 so as to form a flexible connection. Mounted on the inner face of the side rails 12 and 13 is a stop rail 34 which extends downwardly of the rails 12 and 13 a distance less than half the side thereof and half the length thereof. As shown in Fig. 4, the upper window frame is provided on its opposite sides with the groove 35 in which the tongues or rails 34 may engage. In inserting the window frames into the supporting frame, the upper frame is so positioned that the tongue or stop rail 34 engages in the groove 35 and the upper frame is then swung into position, as shown in Fig. 1, the lower frame being retained and swung outwardly as shown in Fig. 4. When the upper frame moves upwardly to its limit, the lower frame may then be swung on the flexible connection into the position shown in Fig. 1 and Fig. 3.

This construction is such as to provide a light and durable storm and screen window supporting frame which may be permanently mounted on the window casing and which would permit the removal of the window frames from the interior of the building, thus facilitating the washing and cleaning of these frames. The structure is also one in which a maximum protection against drafts is afforded.

What I claim as new is:

1. A construction of the class described, comprising: a supporting frame adapted for mounting in a window casing and embodying oppositely disposed side rails and oppositely disposed end rails; a pair of window frames slidably mounted in said supporting frame, one above the other, the upper window frame engaging at its lower side the upper side of the lower window frame; overlapping

tongues on said engaging side of said window frames; an overlapping tongue on the upper rail of said supporting frame overlying the upper rail of the upper window frame; an upwardly projecting tongue on the upper of said window frames overlying the upper rail of said supporting frame; an upwardly projecting tongue on the lower rail of said supporting frame; a tongue on the lower rail of the lower of said window frames for engaging behind said last named tongue; a downwardly projecting tongue on the lower rail of said lower window frame overlying the upper edge of the lower rail of said supporting frame; and resilient means engageable with the upper side of the upper window frame for normally resisting upward movement of said window frames relatively to said supporting frames.

2. A construction of the class described, comprising: a supporting frame adapted for mounting in a window casing and embodying oppositely disposed side rails and oppositely disposed end rails; a pair of window frames slidably mounted in said supporting frame, one above the other, the upper window frame engaging at its lower side the upper side of the lower window frame; overlapping tongues on said engaging side of said window frames; an overlapping tongue on the upper rail of said supporting frame overlying the upper rail of the upper window frame; an upwardly projecting tongue on the upper of said window frames overlying the upper rail of said supporting frame; an upwardly projecting tongue on the lower rail of said supporting frame; a tongue on the lower rail of the lower of said window frames for engaging behind said last named tongue; a downwardly projecting tongue on the lower rail of said lower window frame overlying the upper edge of the lower rail of said supporting frame; and resilient means engageable with the upper side of the upper window frame for normally resisting upward movement of said window frames relatively to said supporting frames.
